W. C. WHITE

WIRELESS SIGNALING SYSTEM

Filed June 5, 1915

Fig. 2.

Inventor:
William C. White,
by Abbott, Davis
His Attorney.

UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

WIRELESS SIGNALING SYSTEM.

Application filed June 5, 1915. Serial No. 32,367.

To all whom it may concern:

Be it known that I, WILLIAM C. WHITE, a citizen of the United States, residing at Schenectady, in the county of Schenectady, 5 State of New York, have invented certain new and useful Improvements in Wireless Signaling Systems, of which the following is a specification.

My present invention relates to wireless 10 signaling systems and more especially to the wireless transmission of speech or other sound waves, such, for example, as those produced by musical instruments.

It has heretofore been proposed to connect 15 a source of continuous high frequency oscillations to an antenna and to modify the waves sent out in accordance with the signals to be transmitted without interrupting their continuity. Difficulty has been experienced, 20 however, in the practical operation of such systems in providing suitable apparatus for controlling a sufficient amount of energy and for producing large enough energy variations in the transmitted waves to reproduce 25 the sound waves at a distant point.

The object of my invention is to overcome 30 this difficulty by providing an organization which will produce continuous waves which are capable of radiating large amounts of 35 energy and which have a large variation in amplitude in accordance with the signals to be transmitted and at the same time provide a system which is easy of adjustment and which is simple and efficient in its operation.

35 The novel features of my invention are pointed out with particularity in the appended claims, the invention itself, however, with further objects and advantages will best be understood by reference to the following 40 description taken in connection with the accompanying drawing in which Fig. 1 illustrates diagrammatically one way of carrying my invention into effect and Fig. 2 shows a modification thereof.

45 As shown in Fig. 1 of the drawing the antenna 1 is grounded as usual. It has connected thereto a source of high frequency oscillations which in this case consists of a high frequency alternator 2. This may be 50 inductively connected to the antenna by means of a transformer 3, or may be connected directly thereto if desired. An inductance 4 which may be varied to tune the

antenna circuit to the desired frequency may be placed in series with the antenna. In 55 some cases it may be desirable to connect the source of energy to the antenna by loosely coupling the primary of the transformer 3 to this inductance. It is a well known fact that with a properly tuned antenna to which 60 is connected a source of high frequency oscillations there exists, because of certain resonance phenomena, a large difference of potential between different points in the antenna circuit. In carrying my inventions 65 into effect I select two such points and connect between these points an energy consuming device 6, which in the case illustrated is an electron discharge relay comprising an exhausted envelope containing 70 an anode 7, a cathode 8 and a conducting grid-shaped body 9 interposed between cathode and anode. In case the antenna itself possesses such a high inductance that little tuning inductance is required one of these 75 points may be found in the antenna itself and it may be desirable to connect one electrode of the electron discharge relay to the extreme end of the antenna as indicated in 80 Fig. 2. In the present illustration the anode 7 is connected to the point 5 at the top of the tuning inductance 4. I prefer to connect the cathode to earth in order to prevent high potentials being impressed upon the telephone transmitter, transformers and batteries employed. 85

The cathode 8 is of filamentary form, preferably of tungsten, and is provided with current for heating it to incandescence by the secondary 10 of the transformer 11 90 which may be supplied with a low frequency alternating current from the mains 12. The temperature of the cathode may be adjusted by means of the variable resistance 13 in the primary circuit of the transformer. The electron discharge device in the present case is one which is adapted for use with high potentials and in order to adapt it to such use it is necessary that the envelope containing the electrodes should be exhausted to such a high degree that when high potentials are impressed upon the electrodes the flow of current between the electrodes is not accompanied by any visible 100 manifestation of gas ionization. When connected in this way to the antenna and when 105

the anode 7 is positive, current will flow through the electron discharge relay 6 and energy will thereby be diverted from the antenna circuit. By varying the amount 5 thus diverted, the amount of energy which will be radiated by the antenna may be varied accordingly. The amount of current flowing through this relay may be varied by varying the potential of the grid 9. If a 10 positive potential is impressed upon the grid the flow of current will be increased while if a negative potential is impressed on the grid the flow of current will decrease. Hence if the grid potential be varied in accordance 15 with potential variations produced by sound waves the amount of energy radiated by the antenna may be varied accordingly. As a means for thus varying the grid potential I have indicated in the present case an ordinary telephone transmitter 14 provided with the usual battery 15 consisting of a few cells and preferably connected to grid 9 through the transformer 16 as indicated, one terminal of the transformer 20 being connected directly to the grid while the other is connected to the middle point of the secondary 10 of the transformer 11 as indicated. In order to secure the best results it will usually be found desirable 25 to adjust the current flowing through relay 6 so that about half of the energy of the source 2 is normally diverted from the antenna circuit. This may be done by impressing an extra potential on the grid 30 9 in addition to that produced by the transformer 16. This extra potential may be derived from the battery 17 and by varying the potential of battery 17 the normal current through relay 6 may be adjusted to 35 the desired value. By this arrangement both the positive and negative half waves of the alternating current produced in the secondary of transformer 16 are effective in varying the amount of energy diverted 40 from the antenna circuit. In order that the currents produced in the secondary of the transformer 16 may not be compelled to flow through the battery 17 a condenser 18 may be inserted in shunt to this battery. 45 In case the potential variations produced in the secondary of transformer 16 are not great enough to produce the desired variation in the amount of energy diverted from the antenna any suitable amplifying means 50 55 may be employed to secure larger potential variations.

In the preferred construction of the electron discharge relay 6 the anode 7 is made up of one or more plates of considerable area 60 and the grid 9 consists of a number of turns of fine wire wound on a supporting framework and located in parallel relation to the anode plate or plates. The cathode 8 is also preferably located in a plane parallel to the grid and anode. The distance be-

tween these members is preferably small and as a result there is an appreciable capacity between them. It will be seen that with the arrangement indicated the anode 7 is alternately positive and negative with respect to the cathode and that as a result the grid 9 will have induced thereon by electrostatic induction positive and negative charges. Altho the grid and cathode are connected electrically the reversals in polarity in these induced charges are so rapid that the potential difference between the two at times may become very large, the secondary of the transformer 16 offering a high impedance to the flow of high frequency charging current between grid and cathode. As a result the positive potential which may be induced on the grid 9 when the anode is also positive may become so great as to allow a large enough current to flow through the relay 6 to divert from the antenna nearly all of the energy from the high frequency source even when no potential is induced upon the grid by means of the telephone transmitter. Also the potentials produced by the secondary of the transformer 16 are in most cases small in comparison to this induced potential and hence will produce little variation in the current flowing through relay 6. In order to overcome this difficulty I employ a tuned circuit comprising a condenser 19 and a variable inductance 20 between the grid 9 and cathode 8. If this circuit is tuned to the frequency of the source 2 it will offer a low impedance to the high frequency charges induced on the grid and in so far as these induced charges are concerned will have the same effect as a short circuit between grid and cathode. Hence the grid and cathode will normally be at substantially the same potential except for the comparatively small difference of potential produced by battery 17. The condenser 19 should preferably be of small capacity so as to offer a high impedance to the comparatively low frequency current produced by the sound waves.

While I have described only two ways in which my invention may be carried into effect it will be apparent to one skilled in the art that many modifications thereof may be made without departing from the scope of the appended claims. While I have illustrated and described an organization in which energy is extracted from only one-half wave of the high frequency current and I have found in practice that speech may be transmitted efficiently with this connection, it will be apparent that by suitable variation in the connections similar apparatus may be operated so as to extract energy from both half waves of the high frequency current. It will also be apparent that the system described may be utilized for transmitting ordinary telegraphic signals as well

- as sound waves by substituting a telegraph key 21 shunted by a high resistance 22 for the transformer 16 as indicated in Fig. 2. What I claim as new and desire to secure by Letters Patent of the United States, is:—
1. The combination in a system for the transmission of wireless signals of an electron discharge relay comprising an anode, a cathode and a grid, means for impressing an alternating potential of high frequency upon the anode of said relay and a circuit including the cathode and grid of said relay which is resonant to the frequency of the potential impressed upon the anode whereby large high frequency potential differences between grid and cathode are prevented. 70
  2. The combination in a system for the transmission of wireless signals of an antenna, a source of high frequency energy connected to said antenna, an electron discharge relay comprising a cathode an anode and a grid, direct electrical connections between said cathode and said anode and points in the antenna circuit between which there is a large difference of potential and a connection between the cathode and grid of said relay which offers a low impedance to high frequency current whereby large high frequency potential differences between grid and cathode are prevented. 80
  3. The combination in a system for the transmission of wireless signals of an antenna, a source of high frequency energy connected to said antenna, an electron discharge relay comprising an anode, a cathode and a grid enclosed in a highly exhausted envelope, a connection between the anode of said relay and a point in the antenna circuit at which a high potential exists, a connection between the cathode and earth and a connection between the cathode and grid of said relay which offers a low impedance to high frequency current whereby large high frequency potential differences between grid and cathode are prevented. 90
  4. The combination in a wireless signaling system of an antenna, a source of high frequency energy connected to said antenna, an electron discharge relay comprising a cathode, an anode and a grid enclosed in a highly exhausted envelope, connections between said cathode and said anode and points in the antenna circuit between which there is a large difference of potential, means for varying the potential of said grid in accordance with signals to be transmitted, and a connection between the cathode and grid of said relay which offers a low impedance to high frequency current but offers high impedance to current of the frequency employed for varying the grid potential to transmit signals whereby large high frequency potential differences between grid and cathode are prevented. 100
  5. The combination in a system for the transmission of wireless signals of an electron discharge relay comprising an anode, a cathode and a grid, means for impressing an alternating potential of high frequency upon the anode of said relay and a circuit including the cathode and grid of said relay which is resonant to the frequency of the potential impressed upon the anode whereby large high frequency potential differences between grid and cathode are prevented. 110
  6. The combination in a wireless signaling system of an antenna, a source of high frequency energy connected to said antenna, an electron discharge relay comprising a cathode, an anode and a grid, electrical connections between said cathode and said anode and points in the antenna circuit between which there is a large difference of potential and a connection between the cathode and grid of said relay which is resonant to the frequency of the source of energy connected to said antenna whereby large high frequency potential differences between grid and cathode are prevented. 120
  7. The combination in a wireless signaling system of an antenna, a source of high frequency energy connected to said antenna, an electron discharge relay comprising a cathode, an anode and a grid, a connection between the cathode of said relay and earth, a connection between the anode of said relay and a point in said antenna electrically remote from earth and a circuit including the cathode and grid of said relay which is resonant to the frequency of the source of energy connected to said antenna whereby large high frequency potential differences between grid and cathode are prevented. 130
  8. The combination in a wireless signaling system of an electron discharge relay comprising an anode, a cathode and a grid, means for impressing an alternating potential of high frequency upon the anode of said relay, means for impressing potential variations of comparatively low frequency upon said grid for transmitting signals and a connection between the cathode and grid of said relay which is resonant to the high frequency potential impressed on the anode but which offers a high impedance to potential of the lower frequency impressed upon the grid whereby large frequency potential differences between grid and cathode are prevented. 140
  9. The combination in a wireless signaling system of an antenna, a source of high frequency energy connected to said antenna, an electron discharge relay comprising an anode, a cathode and a grid enclosed in a highly exhausted envelope, connections between said cathode and earth and between said anode and the end of said antenna electrically remote from earth, and means for varying the potential of said grid in accordance with signals to be transmitted. 150

10. The combination in a wireless signaling system of an antenna, a source of high frequency energy connected to said antenna, an electron discharge relay comprising a cathode an anode and a grid, enclosed in a highly exhausted envelope, connections between said cathode and said anode and points in the antenna circuit between which there is a large difference of potential, 45
5 means for varying the potential of said grid in accordance with current variations produced by sound waves, and a connection between the cathode and grid of said relay which offers a low impedance to high frequency current but offers a high impedance 50 to the current produced by sound waves whereby large high frequency potential differences between grid and cathode are prevented.
10. 11. The combination in a wireless signaling system, of an electron discharge relay comprising an anode, a cathode and a grid, means for impressing an alternating potential of high frequency upon the anode of 55
15 said relay, means for varying the potential of the grid of said relay in accordance with current variations produced by sound waves and a connection between the cathode and grid of said relay which offers a low impedance to high frequency current but 60 which offers a high impedance to the current which is varied by sound waves whereby large high frequency potential differences between grid and cathode are prevented.
10. 12. The combination in a wireless signaling system of an antenna, a source of high frequency energy connected to said antenna, an energy consuming device comprising a cathode, an anode and a grid, electrical connections between said cathode and said anode, and points in the antenna circuit between which there is a large difference of potential and a connection between 65
